(57) **CLAIM**

The ornamental design for a knit footwear upper, as shown and described.

DESCRIPTION

FIG. 1 is a side perspective view of a knit footwear upper showing my new design;

FIG. 2 is a side elevational view thereof;

FIG. 3 is an opposite side elevational view thereof;

FIG. 4 is a front elevational view thereof;

FIG. 5 is a rear elevational view thereof;

FIG. 6 is a top plan view thereof;

FIG. 7 is a bottom plan view thereof;

FIG. 8 is a side perspective view of a second embodiment of a knit footwear upper showing my new design;

FIG. 9 is a side elevational view thereof;

FIG. 10 is an opposite side elevational view thereof;

FIG. 11 is a front elevational view thereof;

FIG. 12 is a rear elevational view thereof;

FIG. 13 is a top plan view thereof; and,

FIG. 14 is a bottom plan view thereof.

The cross-hatched shading in FIGS. 1-14 represents a soft knit or crocheted material that forms the footwear upper. The broken lines in FIGS. 1-14 represent portions of the footwear that form no part of the claimed design. The broken lines which define the bounds of the claimed design form no part thereof.
